UNITED STATES PATENT OFFICE.

JAMES FRANK DURYEA, OF SPRINGFIELD, MASSACHUSETTS.

CARBURETER FOR EXPLOSIVE-ENGINES.

SPECIFICATION forming part of Letters Patent No. 699,504, dated May 6, 1902.

Application filed November 30, 1900. Serial No. 38,079. (No model.)

To all whom it may concern:

Be it known that I, JAMES FRANK DURYEA, a citizen of the United States of America, and a resident of Springfield, in the county of 5 Hampden and State of Massachusetts, have invented certain new and useful Improvements in Carbureters for Explosive-Engines, of which the following is a full, clear, and exact description.

10 This invention relates to improvements in carbureters more especially designed for use in conjunction with gasoline-engines, and has for its object the production of an apparatus which may be nicely regulated with respect to its capabilities for supplying required 15 proportionate quantities of the liquid fuel and air in vaporized form and which is automatic in respect to the maintenance therein of a uniform quantity of the liquid fuel.

20 The improved carbureting apparatus consists in the constructions and arrangements or combination of parts hereinafter described in connection with the accompanying drawings and as set forth in the claims.

25 In the drawings, Figure 1 is a plan view, and Fig. 2 is a central vertical sectional view.

In the drawings, A represents the tank or font of the carbureter, which is shown of a cylindrical form, having a closed bottom and 30 receiving in the screw-threaded top thereof the closing-cap a. The walls of the carbureter-tank at opposite sides are thickened or built out, as indicated at b b², and in the base at the one side through the thickened portion 35 is a horizontal passage d, leading into the tank-chamber and outwardly closed by the removable screw-plug c. At the opposite side the tank has the horizontal chamber extension d².

40 B represents the gasoline-supply pipe, connecting, by a minute opening e, with the passage d. Above and in line with the said pipe B and inlet-duct e within the solid or thickened wall of the tank is a vertical socket or 45 hole f, the same leading from the top of the tank to the passage d, and in this socket f is fitted, for a rising-and-falling play, a rod g², the lower attenuated extremity g of which constitutes the valve for the gasoline-inlet e.

50 h represents a lever intermediately pivotally mounted at h² within the tank, one extremity of which has a lifting engagement under the valve-rod g², while on the other arm of the

said lever rests the float C. In the thickened portion b² of the wall of the tank is constructed 55 the upwardly-opening cylindrical chamber D, in the base of which is fitted the upstanding nozzle i, having a contracted opening leading from its lower to its upper end. In the base-wall k of the said cylindrical chamber D 60 a horizontal passage j is drilled, the same intersecting the vertical passage m, which is drilled down through the solid metal between the tank proper and the chamber D. The lower end of the said passage m has communication with the interior of the tank A by reason of its extension beyond the place of intersection with the passage j for connection with the tank-chamber extension d². The 65 said passage m being drilled with two diameters, a valve-seat is constituted at n, against which or adjacent which the lower tapered end of the rod o may have its position. The 70 said rod has a portion o² thereof constructed with a thread engaging in the threaded portion m² of the said passage m, so that by turning the rod o—the same having a slotted head 75 o³ for facility therefor—the passage of gasoline from the tank-chamber through the passage j and upwardly through the nozzle i may 80 be more or less free, as desired.

p represents a screw-plug for closing the outer end of the passage j.

r represents a seat or shoulder constituted by a ledge formed in the inner wall of the vertical cylindrical chamber D. Below this ledge or shoulder the casting for the apparatus comprises the lateral hollow hub-like extension or pipe-section E, the opening therethrough being comparatively large, the same, as indicated, having a diameter about the same as that of the said chamber D. Through this conduit E air from the exterior of the carbureter freely enters into the lower portion of the chamber D. Seated on the aforementioned rest or shoulder r are the radial arms or wings s s, which are outwardly extended from the axially-vertical ring F. Above this ring F is an externally-cylindrical annular shell G, the opening through the lower portion thereof being downwardly flaring, as indicated at t.

The side wall of the chamber D has the vertically-extending opening or slot u, through which projects the threaded shank of the 105 screw v, the cylindrical head of which has

its location outside of the chamber-inclosing wall, while the threaded shank-screw engages into the tapped socket therefor in the annular shell G.

5 In the use of the carbureter described the same is combined with a storage or supply-tank of gasolene and with the inlet of the cylinder or cylinders of the motor or engine. The connection which the carbureter-tank or service-tank A has with the gasolene-supply is by the pipe B, which may lead from connection with the supply-tank from a location higher than the carbureter, whereby there may be a pressure of the gasolene in an upward direction at or through the passage e. When the ingress of gasolene into the tank A establishes the requisite liquid-level therein, the float C is lifted, relieving the lever h of the weight thereof, so that the valve g will automatically 10 close and for the time prevent further ingress of the liquid fuel into the service-tank or main chamber of the carbureter. It being understood that the upper portion of the chamber D has by any suitable conduit or pipe extension connection with the inward valve of the motor, when the motor-piston moves on its suction-stroke, a suction force is created in the upper part of the chamber D, which has the effect to draw air and gasolene together 15 into the cylinder-chamber, the gasolene coming by way of the nozzle i and passage j from the carbureter-tank, while the air comes from the exterior of the apparatus through the air-inlet E and passes upwardly as to some part 20 thereof through the opening within the ring F, and as to some part thereof through the spaces between the radial wings s s. By loosening the screw v, and through it moving the annular shell G vertically, such shell may 25 have its position in contact against or considerably removed from the upper outer edge of the ring F, whereby the passage of air upwardly exteriorly of the ring may be cut off or rendered more or less free, as desired, and 30 the copiousness of the passage of the gasolene through the duct j and upwardly through the nozzle i may be regulated by raising or lowering the screw-provided valve-rod o.

As will be apparent from an inspection of 35 the drawings accompanying this specification, the apparatus constituting the carbureter consists as to a large portion thereof of a single casting comprising the service-tank and the chamber D to the side thereof, while 40 the ducts, socket, and fittings combined with the casting are such as may be simply and cheaply produced. Moreover, all internal parts which may possibly become clogged are 45 readily accessible by the removal of the screw-plugs c and p or the rods g² or o and, if necessary, the nozzle i.

If desired to change the sensitiveness of 50 the float-regulated gasolene-ingress, ring-shaped weight or weights may be placed on 55 the upper end of the valve-rod g², an annular shoulder for the support of such weights being indicated at g³ in Fig. 2.

Having thus described my invention, what I claim, and desire to secure by Letters Patent, is—

70 1. In a carbureter, the combination of a mixing-chamber having a longitudinal slot in its side wall, a partition-ring in the chamber having a central axial aperture and also other apertures, an inlet-pipe arranged to discharge hydrocarbon in said central aperture, a movable collar located in the chamber above said ring and arranged to control said other apertures in the partition by its axial movement, said collar being so disposed as to cover said slot in its several positions, and a screw secured to the collar and projecting through the slot, the screw being arranged to adjust the collar from the outside of the carbureter and also to clamp the collar in its positions of adjustment.

75 2. In a carbureter, the combination of the chamber, D, having the slot, u; the ring, F, having a central aperture and also the apertures, s; the nozzle, i, arranged to discharge hydrocarbon in said central aperture; the ring, G, arranged to move axially and thereby control said apertures, s; the ring being so disposed as to cover the slot, u, in its various positions; and the screw, v, tapped into the ring, G, and projecting through said slot; said screw being arranged to move the ring, G, and to clamp it in its positions of adjustment.

80 3. In a carbureter, the combination of a mixing-chamber, a partition-ring in the chamber having a central axial aperture and also other apertures, an inlet-pipe for the hydrocarbon arranged with its discharge end located in said central aperture, a movable collar located in the chamber above said ring and arranged to control said other apertures in the partition by its axial movement, said collar having its lower edge tapering upwardly toward its axis, said partition having the part in apposition to said tapering portion of the collar of a corresponding taper, means for moving the collar axially, and means for securing the collar in its positions of adjustment.

85 4. In a carbureter, the combination of the chamber, D; the ring, F, having a central aperture and also other apertures, s; the nozzle, i, arranged to discharge hydrocarbon into the central aperture; the ring, G, arranged to move axially and having its lower edge tapering upwardly toward its axis; the ring, F, having the upper face forming the margins of the apertures, s, of a taper corresponding to the tapering part of the collar, G; means for moving the collar, G, axially; and means for securing the collar in its positions of adjustment.

90 Signed by me at Springfield, Massachusetts, in presence of two subscribing witnesses. J. FRANK DURYEA.
